Patented May 10, 1921.

UNITED STATES PATENT OFFICE.

BRAYTON C. GRINNELL, OF SEATTLE, WASHINGTON.

GLOVE.

1,377,338.

Specification of Letters Patent. Patented May 10, 1921.

Application filed July 31, 1920. Serial No. 400,441.

To all whom it may concern:

Be it known that I, BRAYTON C. GRINNELL, a citizen of the United States, residing at Seattle, in the county of King and State 5 of Washington, have invented a certain new and useful Improvement in Gloves, of which the following is a specification.

My invention relates to improvements in gloves and more particularly to gloves made 10 of leather and canvas, but applicable to gloves made of any other suitable material, and the object of my invention is to provide a working glove of the back seam type wherein the palm portion of the glove is cut 15 or stamped separately from the palm fourchettes of the glove fingers so that the maximum number of pieces may be obtained from a skin or hide and which also permits of small pieces of material being utilized for 20 the palm portion where heretofore it has been found impractical to use the same for this purpose.

Another object is to provide a four fourchette glove wherein the palm fourchettes 25 of the fingers are joined to the upper edge of the palm portion of the glove in such a manner that the resultant joining seam is disposed adjacent the bases or last joints of the fingers of the wearer being adapted when so 30 disposed to fit in the crevices formed by the fingers and palm when the wearer's hand is flexed.

A further object is to provide a four fourchette glove, embodying the maximum of 35 flexibility, simplicity, economy and durability in construction, that embodies the maximum of comfort, and that is not objectionable to the wearer while in use or when his hand is flexed.

With the above and other objects in view 40 which will appear as the description proceeds, my invention resides in the novel construction, combination adaptation and arrangement of parts hereinafter described 45 and claimed.

I accomplish these objects by devices illustrated in the accompanying drawings, wherein:—

Figures 1, 2, 3 and 4 are plan views or 50 profiles of blanks from which the inner or

palm fourchette members, for the first, second, third and fourth fingers respectively of my gloves are formed.

Fig. 5 is a plan view or profile of the blank from which the inner member or palm 55 side of the thumb of my glove is formed.

Fig. 6 is a plan view or profile of the blank from which the main or palm portion of my glove is formed.

Fig. 7 is a view of the palm side of a 60 glove embodying the features of my invention and illustrating more clearly the method of joining the finger fourchettes to the palm portion.

Fig. 8 is a view of the rear or back side 65 of the glove, illustrating the method of securing the seamless finger ends or tips of my glove, and,

Fig. 9 is a view in vertical transverse section of a detail of my invention taken on a 70 broken line 9—9 of Fig. 7.

Referring to the drawings throughout which like reference numerals indicate like parts, the numerals 10, 11, 12 and 13 indicate the palm fourchette blanks for the first, 75 second, third and fourth fingers respectively of my improved glove, all of which are cut or stamped from the desired flexible material substantially in the shape shown.

The numeral 14 indicates the blank for 80 the palm side of the thumb of my glove and 15 indicates the blank for the palm portion of my glove both of which are cut or stamped from the desired flexible material substantially in the shape shown.

The back 16 of my improved glove comprises in integral form the rear or back portions 17 for the first, second, third and fourth fingers respectively, the back portion 18 for the thumb of the glove may be formed 90 integral with the back 16 if desired, or cut separately and sewed thereto as shown as at 19 in Fig. 8. The back 16 with its associated back portions 17 and the back portion 18 for the thumb are cut substantially in the 95 shape shown in Figs. 7 and 8 from a sheet of canvas or other suitable or desired material.

To form a glove of the back seam type I have provided the palm fourchette blanks 100

10, 11, 12 and 13 with border portions 20, which portions 20 normally lie beyond the profile of the fingers of the glove, which are indicated by dot and dash lines in Figs.

5 1 to 4.

The inner border portion 20 of the fourchette blank 10 is cut with a triangular prolongation 21, the borders 20 of the fourchette blank 11 are cut with triangular prolongations 22 and 23, the borders 20 of the fourchette blank 12 are also cut with similar prolongations 24 and 25, and the inner border 20 of the fourchette blank 13 is cut with a triangular prolongation 26.

15 In fabricating the glove the edge portion 27 of the prolongation 21 is stitched to the edge portion 28 of the prolongation 22 in such a manner to form an inseam as shown at 29 see Figs. 8 and 9. The edge portion 30 of the prolongation 23 and the edge portion 31 of the prolongation 24 are similarly stitched together to form an inseam 32, see Fig. 8, and the edge portion 33 of the prolongation 25 is stitched to the edge portion 34 of the prolongation 26 to form an inseam 35, see Fig. 8.

The edge portion 40 of the fourchette 10 and the edge portion 41 of the palm portion 15 are cut with a slight curve as shown 30 and are adapted to be stitched together to form an inseam 42, see Figs. 7 and 8. The edge portion 43 of the fourchette 11 and the edge portion 44 of the palm portion 15 are cut in the manner shown and are stitched 35 together to form an inseam 45, see Figs. 7 and 9. The edge portion 46 of the fourchette 12 and the edge portion 47 of the palm portion 15 are cut as shown and are stitched together to form an inseam 48, see 40 Fig. 7, and the edge portion 49 of the fourchette 13 and the edge portion 50 of the palm portion 15 are also cut in the manner shown and are stitched together to form an inseam 51, see Fig. 7.

45 The edge portion 52 of the thumb blank 14 and the edge portion 53 of the palm portion 15 are cut as shown and are stitched together to form an inseam 54, see Fig. 7.

In order to eliminate the crowded seams 50 at the ends of the fingers, where they are exposed to considerable wear and frequently rip the palm fourchette blanks 10, 11, 12 and 13 are provided or cut with prolongations 55, which prolongations 55 are, when 55 the glove is fabricated turned over the ends of the fingers and stitched to the upper ends of the finger portions of the back 16 to form seams 56 across the back of each finger as shown in Fig. 8. The width of the prolongation 55 is slightly less than the width 60 of the border portions 20 as shown, the edges 57 of the said prolongations 55 being stitched to the upper edge portions of the said border portions 20 to form inseams 58, 65 see Fig. 8.

The thumb blank 14 may be also cut if desired with a prolongation on its tip similar to the prolongations 55 shown and described for the fourchette blanks.

The edge portions of the borders 20 are 70 stitched to the edge portions of the finger portions of the back 16 to form seams 59 which are normally disposed at the back of the glove; see Fig. 8. The edge portions 60 of the palm portion 15 are stitched to the 75 back 16 to form seams 61, see Figs. 7 and 8.

The outer edge portion 62 of the thumb blank 14 is stitched to outer edge portion of the canvas thumb back 18 to form a seam 63, see Fig. 7.

80 The wrist portion of the glove may be finished in any desired manner as for example with a knitted cuff 64 as shown.

The essential feature of my invention resides in the cutting of the palm portion of 85 the glove and the fourchettes of the same separately, so that, the maximum number of pieces may be obtained from a given amount of material, also permitting of scraps of material being utilized for the palm portion 90 where heretofore it has been found uneconomical and impractical to use the same for this purpose, thus reducing the cost of manufacturing the glove to the minimum.

In practice I have found that a glove 95 constructed in accordance with my invention is extremely comfortable to wear, even when made from heavy thick material, that the seams formed by the joining of the fourchettes to the palm portion are so disposed 100 as not to be objectionable to the wearer while the glove is in use or when the wearer's hand is flexed.

105 While I have shown and described the features of my invention as applied to a working glove of the back seam or seamless class, I desire to have it understood that the said features may be applied to a glove of any class and to a glove that is sewn in any manner.

110 From the foregoing description taken in connection with the accompanying drawings, the advantages of the construction and of the method of operation of my improved glove will be readily apparent to those skilled in the art to which the invention relates, but, while I have described the principle of operation of the invention, together with the structure which I now consider to be the best embodiment thereof, I desire to 115 have it understood that the glove shown is merely illustrative and that such changes may be made when desired as are within the scope of the invention.

120 What I claim is:—

125 An article of manufacture, a back seam glove comprising a palm portion, four finger fourchettes adapted to be attached to the said palm portion to form a continuous seam adapted to be disposed adjacent the base of 130

the fingers to fit in the crevices formed by the said fingers and palm of the wearer, the said finger fourchettes having prolongations extending beyond the upper extremity 5 of each fourchette which prolongations are adapted to be turned over the ends of the fingers, a back for the said glove having integral back portions for the said finger

fourchettes which are adapted to be attached on their upper ends to the turned 10 over ends of the said prolongations, and a thumb member for the said glove.

In witness whereof, I hereunto subscribe my name this 24th day of July A. D. 1920.

BRAYTON C. GRINNELL.
